PETROLEUM WICK BURNER

Karl Humpoletz, Vienna, Austria, assignor to the firm of Lampen- und Metallwarenfabriken R. Ditmar Gebrüder Brünner A. G., Vienna, Austria, a joint-stock company of Austria

Application November 9, 1929, Serial No. 406,075
In Austria November 10, 1928

1 Claim. (Cl. 158—94)

This invention relates to petroleum wick burners for non-luminous flame of the type where-in a flame regulator surrounds the top end of the wick projecting out of a wick guide and carries 5 a combustion chamber enclosing the flame. The flame regulator is provided with one or more apertures above which the flame burns, which flame is prevented by said flame regulator from striking back to the portion of the wick between 10 said regulator and the wick guide.

In arrangements hitherto known said flame regulator rests loosely upon the top end of the wick and it is, therefore, difficult to secure a correct position of the regulator relatively to the 15 wick. When the regulator is in an incorrect position excess air may then pass into the flame between the flame regulator and the top end of the wick, thereby causing soot-bearing strips in the flame.

20 The invention has for its object to fix the flame regulator so that it acts as a stop for the travel of the wick. By raising the wick, the upper end of the latter strikes against the flame regulator held in correct position whereby the top end of 25 the wick is enlarged and fills completely the apertures of the regulator, so that passing of an uncontrolled amount of excess air into the flame is automatically prevented.

Some modifications of devices for fixing the 30 position of the flame regulator are illustrated in the accompanying drawing. In the drawing Fig. 1 is a sectional elevation of the device, Fig. 2 is a sectional elevation of a modified form of the device. Fig. 3 is a sectional elevation of another 35 modified form of the device, in which the flame regulator is secured to a stationary part of the burner.

1 denotes the uppermost part of the fuel reservoir, 2 the round wick, 3 and 4 guiding tubes 40 for the wick, 5 a ring connected to the fuel reservoir, and 6 the flame regulator. The latter is provided with apertures 6a which leave un-covered the top end of the wick and which are separated from each other by bridge-pieces 6c, 45 and air-supply apertures 6b, provided in the side walls; 7a and 7b are the perforated jackets which are mounted upon the flame regulator and surround the combustion chamber. 8 is a protective casing releasably connected with the ring 5 for 50 keeping away gusts of wind, this casing being united with the casings 7a and 7b into a unitary whole, by means for example of a transverse rod passing through them.

The travel of the wick is limited in this construction by a positioning nut 9, which can be

screwed upon a guiding pin 10 rigidly connected with the inner wick guiding tube by a bearing 11.

When turning the wick 2 up, its upper margin is pressed against the apertures 6a of the flame regulator 6, and the latter is thereby pressed 60 against the suitably adjusted positioning nut 9. The wick then fills the apertures 6a completely and bears against the bridge pieces 6c and against the walls of the flame regulator bounding the apertures 6a. In this way on the one hand the 65 upward movement of the wick is limited, and on the other hand access of air through the apertures 6a is prevented. The apertures 6b, however, for the admission of air and petroleum vapours into the combustion chamber remain 70 free.

The air necessary for the complete combustion of the petroleum vapours passes on the one hand through the inner air-supply pipe formed by the wick tube 3, through the perforated bottom 75 of the flame regulator and through the holes in the jacket 7a, and on the other hand through the ring 5 and the outer jacket 7b into the combustion chamber.

For ignition purposes the jackets 7a, 7b and 80 8 are raised, and the wick is turned up until the edge of the wick presses against the apertures 6a of the flame regulator.

By rotating the positioning nut 9 the correct 85 position of the flame regulator in relation to the wick margin can easily be effected. This position remains constant when the burner is repeatedly employed, and the flame is steady.

In the constructional example according to 90 Fig. 2 the limiting stop is in permanent connection with the fuel reservoir 1 and is formed by the bent upper edge of the burner ring 5. The flame regulator 6 is provided with a perforated annular flange 6d which surrounds the latter and which strikes in its highest position 95 against said edge of the ring 5, when the turned up wick has entered the flame regulator 6 and has closed the holes 6a therein, the end of the wick being somewhat expanding in breadth.

The example of construction according to Fig. 100 3 shows a flat wick burner, the wick of which is surrounded by a flame regulator 6, which under its upper end, which is open and bridged over by bridge pieces 6c, has a constriction 6e, and under the latter the air-admission apertures 6b, 105 through which the air necessary for combustion passes into the combustion chamber surrounded by the perforated jacket 7 and to the flame, whereas uncontrolled amounts of superfluous air which would cause sooting of the flame are kept 110

away by the wick bearing against the constriction.

A perforated cap 6d forming one piece with the flame regulator 6 is provided with an angle 5 slot 6f, into which a pin 5a projecting inwardly from the ring 5 is movable in the manner of a bayonet joint, thereby fixing the flame regulator. In this case the flame regulator does not move with the wick but is already secured in a 10 definite position corresponding to the uppermost position of the wick during the operation of the burner.

What I claim is:—

A petroleum wick burner, comprising a fuel 15 container, a wick guide, a wick projecting out of said guide, a flame regulator spaced from said

wick guide and having the form of a sleeve embracing and extending over the top of the wick and diverging downwards, said flame regulator having apertures leaving uncovered the top end of the wick, and other apertures arranged below the first named apertures and serving for the passage of air and petroleum vapors developed from said wick, perforated walls forming a combustion chamber arranged above said flame regulator, supporting means cooperating with the flame regulator for detachably holding the flame regulator in a fixed position with respect to the wick guide and container and the last mentioned apertures opening into the combustion chamber.
